TO MOTOR AND PLANE ACCESSORIES, INC., OF DETROIT, MICHIGAN, A CORPORA-
TION OF DELAWARE

LUBRICATING SYSTEM

Application filed April 8, 1927. Serial No. 181,907.

This invention relates to lubricating systems by which a supply of lubricant, such as oil, maintained at a central point may be distributed in suitable quantities to a number of different elements at a distance from the supply, which require lubrication. More particularly, the invention is concerned with a system especially adapted for use in a motor car and including a central reservoir and lines leading therefrom to the different parts of the car which require lubrication, such as the spring shackles and the like. An adaptation of the invention suitable for this purpose will accordingly be described, though it is to be understood that the utility of the system is by no means limited to that particular use.

In the modern motor car there are many points on the chassis which have more or less movement when the car is in operation and therefore require continual lubrication. Heretofore the oiling or lubrication of these parts has in some instances been accomplished by the use of oil or grease cups, requiring constant replenishment and attention, and as these cups are frequently placed at points such that they are accessible only with difficulty, it is a laborious operation to keep the cups filled and in operating condition. As a consequence, one or more of these cups are frequently overlooked and run dry, thus resulting in the car wearing rapidly and also becoming noisy.

Attempts have been made to solve this problem by the installation of piping systems connected to a central reservoir and leading to the different points where lubrication is required, and in some of these systems the distribution of the oil is accomplished by means of a pump of suitable form which is operated at intervals by the driver. While these systems simplify the supplying of oil, the central reservoir not only requires replenishment from time to time, but the actual supplying of the oil depends on the manipulation of the pump by the operator and such attention is frequently overlooked.

The present invention is directed to the provision of an oiling system for use in

motor cars, which is entirely automatic in operation, which is brought into action to supply lubricant to the parts which require it whenever the motor is operated, and which automatically stops the delivery of the lubricant when the motor is stopped. In this system there is included a central reservoir or tank for the lubricant from which extend mains or conduits leading to the different delivery points. This reservoir is capable of being sealed and is placed beneath the hood of the car, where it is readily accessible and yet unnoticeable. The conduits are oil-tight and preferably include a fibrous strand or wicking which extends from the reservoir to the delivery point where the strand may be in contact, if desired, with the surface to be lubricated. The tank is placed in such position that it is exposed to heat developed by the engine when the latter is operating and preferably the tank is water-jacketed and mounted so that the water jacket forms a part of the line between the water jacket of the engine and the radiator. Accordingly, when the motor is in operation, water circulating through the system flows through the jacket around the tank and the oil becomes heated. When the motor is stopped, the flow of water ceases and the tank cools.

In operation a quantity of oil is placed in the reservoir and the latter is then sealed. The heat developed by the motor when operating is transmitted by the water to the contents of the tank and heats the oil therein and also any air which lies above the surface of the oil. The heat thus applied causes an expansion of the fluid within the tank, and this pressure starts the flow of oil through the conduits. The oil flow is in part due to capillary action through the strand and after a short period of motor operation, oil is flowing through the entire strand to the delivery points. The heat of the motor causing the expansion of the fluid and the generation of pressure in the tank not only starts the flow of oil, but facilitates the flow in that it renders the oil more fluent. The flow of oil through the conduits continues so long as the motor is in opera-

tion, but when the motor is stopped and cools down, the lubricant and air within the tank cool and contract, thus creating a slight vacuum which draws back the lubricant through the strand away from the delivery points. The flow of lubricant through the strand is now prevented by the vacuum action and no flow occurs while the motor is at rest, or else flow is permitted to so limited an extent that no waste of any consequence occurs.

A system operating in accordance with the principles of the invention is entirely automatic, and the only attention required is the occasional replenishment of the oil. Owing to the fact that the oil is delivered to the points which require lubrication with a slow but continuous flow throughout the operation of the motor, these parts are thoroughly lubricated when the car is in use without waste or dripping. Also, by placing the tank adjacent the radiator, the connections are simplified and the tank and its jacket may be constructed conveniently as an integral extension from the chamber at the top of the radiator.

For a better understanding of the invention, reference may be had to the accompanying drawings, in which

Fig. 1 is a plan view, largely diagrammatic, of a portion of a motor car chassis, showing the installation of parts of the system,

Fig. 2 is a side view, partly in section, showing the details of the system,

Fig. 3 is a sectional view on an enlarged scale, showing the main reservoir and its connections, taken on the line 3-3 of Fig. 2,

Fig. 4 is a view in elevation of a spring shackle illustrating the manner of supplying lubricant thereto, and

Fig. 5 is an enlarged sectional view of a connection in the conduit line.

In the drawings, the motor car chassis is illustrated conventionally, the chassis including side frame members 10 of the usual channel section connected by cross members 11, of which only one is shown. The car has the usual motor 12 having a water jacket from which a connection 13 leads to the chamber 14 at the top of the radiator 15. At the bottom of the radiator is a connection 16 leading to the engine water jacket, and in this connection may be a pump 17 of any suitable form to assist in the oil flow. Behind the radiator is mounted the usual fan 18.

The different parts of the car, such as the spring shackles and the like, which require lubrication are supplied with lubricant from a main reservoir or tank 19 having a cover 20 by which the tank may be tightly sealed, this cover having a filler opening provided with a cap 21. The tank

is provided with a water jacket 22 and the water jacket is placed to form a part of the connections between the engine water jacket and the radiator. Preferably the tank is placed in the connection through which the hot water flows from the cylinder head to the top of the radiator, and the tank, with its jacket, may conveniently be formed as an extension from the radiator itself. With the arrangement illustrated in Fig. 2, the tank occupies a space beneath the hood not otherwise used, and the tank is readily accessible for refilling. At the same time the connections are simplified, the cost of installation much reduced, and the tank is thoroughly heated by the direct flow of hot water through its jacket.

The cover of the tank is provided with one or more tubes 23 generally of siphon form, these tubes passing from within the tank at a point near the bottom thereof and below the normal liquid level up through the top, then downwardly below the tank to connect with an oil conduit 24 mounted on a side member of the chassis. Ordinarily each side member will carry a conduit 24 which has branches leading to the different points where lubrication is required, and a single tube 23 may supply oil to these lines by a cross connection. Instead of that arrangement, two tubes 23 may be employed, one leading to each of the main longitudinal lines 24.

Within the tube 23 is a conducting strand 25 which is preferably of a fibrous material such as cotton gauze fabric of the type known as bandage material, asbestos rope, and various other materials of that kind. The purpose of this strand or wick is to provide a conducting medium through which the oil may flow by capillary attraction and numerous materials suitable for the purpose and similar to those mentioned will be recognized as useful for the purpose. This strand should substantially fill the tube in which it is placed and is preferably loosely matted together.

Such a strand as this is placed in the tube 23 which has a siphon form, also in the main lines 24, and in the branch lines leading from the main lines to the points where lubrication is required. An end of the strand 26 may project beyond the intake end of the siphon tube 23 in the oil tank, and this strand leads through the siphon tube to the point where that tube is connected by a T 27 to one of the main conduits 28. Within the conduit 28 is another strand 29 similar to the strand 25 and in contact with the end thereof, so that oil may flow freely from one strand to the other. Similar strands are placed in the branch lines with their ends in contact with the strand 29 and these strands in the branch line may project slightly beyond the ends of the lines

and contact with the surfaces where the oil is to be delivered. This arrangement is shown in Fig. 4, where the branch line 30 leads to the shackle bolt 31 which has an opening 32 in which the end of the strand 5 may extend. The end of the strand bears against the surface of the bolt, as illustrated, to deliver oil thereto and the shackle may be drilled lengthwise, as shown at 33 to deliver oil to the bearing in which the lower bolt 34 is mounted. A similar arrangement 10 may be used at other places on the chassis where oil is required, the filament or strand preferably extending out of the tube a slight 15 distance and contacting with the surface over which the oil is to be distributed.

In the system as described, a quantity of oil is maintained in the pressure tank and air is trapped above the oil when the tank 20 is sealed. When the motor is started and the hot water in the cooling system flows through the water jacket around the tank, heat is transferred to the oil and air within the tank and the oil and air expand and pressure is generated. The pressure causes oil 25 to be forced out of the tank through the tubes 23 and so long as the motor is operating and there is pressure in the tank, the flow of oil continues. This flow may in part be assisted by capillary action in the strand. 30 The oil flows through the delivery lines to the surfaces to be lubricated and the delivery of oil is slow but continuous. The strand within each line is permeated with oil and 35 the delivery of oil at the bearings is to some extent dependent on the rate at which oil is taken from the end of the strand and distributed over the surfaces which require it.

When the motor is shut down and cools 40 off, the temperature of the contents of the tank is lowered and since some oil has been discharged from the tank, a partial vacuum is created. This tends to draw oil back through the delivery lines into the tank but 45 the vacuum is broken in the course of time by air which flows back through the line into the tank. The partial vacuum tends to retract oil from the ends of the delivery lines and in actual operation, the ends of 50 the strands at the ends of the lines are fairly dry during the period when the tank is cooled after a period of operation.

The system, it will be observed, is automatic in operation and the only attention 55 required is for the replenishment of oil from time to time. By mounting the tank in such a way that its water jacket forms a part of the connections in the water circulating system, with the tank preferably 60 placed between the engine and the radiator, the tank is immediately exposed to heat as soon as the motor operates, and thus the system comes at once into action as the car 65 is used. In most automobiles as now constructed, the radiator is provided with a

chamber at the top so arranged that the tank and its water jacket may be mounted to form an integral part thereof. This simplifies the piping connections and places the tank at a point where it is readily accessible. 70 At the same time the tank is out of the way and does not occupy space which would ordinarily be used for other purposes. The cost of installation of the system is relatively low, and as the oil is conducted through the strand, the oil lines do not have to be absolutely oil-tight. If a breakage occurs in any of the lines, oil is conveyed across the break through the strand so that leakage or dripping is avoided. The system may be 75 said to be practically dry because only a small quantity of oil is present in the piping at any time and this oil is entirely taken up by the strand. For this reason the system differs in important respects from similar 80 systems in which lubricant is distributed through lines by a pump operated by the driver, and all the lines are filled with lubricant at all times. In the present system, since the oil is delivered only in small quantities a relatively small size tank will contain 85 all the oil needed for a long period of use.

I claim:

1. In a motor car, the combination with the water-jacketed engine, of a radiator, 90 connections between the top of the radiator and the engine jacket, a sealed tank for oil mounted between the engine and the radiator and having a jacket forming a part of said connections for the flow of water between the engine jacket and radiator in heat 95 exchange relationship to the contents of the tank, and a conduit for oil leading from the tank to the parts of the car requiring lubrication, the flow of water through the tank jacket delivering heat to the contents of the tank when the car is in operation which develops pressure in the tank initiating the flow of oil, the oil flow being stopped when the pressure is released due to the cooling 100 of the contents of the tank when the engine is shut down.

2. In a motor car, the combination with the water-jacketed engine, of a radiator, 105 connections between the radiator and the engine jacket, a sealed tank for oil mounted to form an extension of the radiator and having a jacket for the flow of water between the engine jacket and radiator in heat exchange relationship to the contents of the tank, and a conduit for oil leading from the tank to the parts of the car requiring lubrication, the flow of water through the tank jacket delivering heat to the contents of the tank when the engine is in operation which develops pressure in the tank initiating the flow of oil, the oil flow being stopped when the pressure is released, due to the cooling 115 of the contents of the tank when the engine is shut down.

3. In a motor car, the combination of a water-jacketed engine, a radiator, connections between the radiator and the engine jacket, a sealed tank for oil mounted between the engine and the radiator and having a jacket forming part of the said connections through which water flows in heat exchange relationship to the contents of the tank, a conduit for oil having an intake end within the tank near the bottom thereof and extending above the liquid level in the tank and leading to a point below the tank level, a line connecting the conduit with a point on the car which requires lubrication, and a strand within the conduit and line serving as a conductor for oil, the delivery of heat to the contents of the tank upon the initiation of engine operation generating pressure within the tank which starts the flow of oil through the strand, the release of pressure due to the cooling of the tank upon stoppage of the motor serving to stop the further flow of oil through the strand.
4. In a motor car, the combination of an engine having a water jacket, a radiator, connections between the radiator and the engine jacket, a sealed tank for oil mounted to form an extension of the radiator at the top thereof, this tank having a jacket through which water flows between the engine jacket and the radiator in heat exchange relationship with the contents of the tank, a conduit for oil leading from a point in the tank below the normal liquid level to a point above the said level and then downwardly below the tank, a line leading from the conduit to the points on the car which require lubrication, a strand extending through the conduit and the line, this strand being of loosely matted material and serving as a conductor for the oil through which the oil may flow in part by capillary attraction, the flow of oil being initiated by the transfer of heat to the contents of the tank when the motor is started resulting in the generation of pressure in the tank, and the flow of oil being stopped when the motor is stopped by the release of pressure due to the cooling of the tank contents.

In testimony whereof I affix my signature.
JOHN J. O'BRIEN.
